UNITED STATES PATENT OFFICE

RICHARD F. KRAUSE, OF MASSILLON, OHIO

DESIGN FOR A DRIP COFFEEPOT

Application filed March 21, 1932. Serial No. 43,255. Term of patent 14 years.

To all whom it may concern:

Be it known that I, RICHARD F. KRAUSE, a citizen of the United States, residing at Massillon, in the county of Stark and State of Ohio, have invented a new, original, and ornamental Design for Drip Coffeepots, of which the following is a specification, reference being had to the accompanying drawings, forming part thereof.

Fig. 2, a top plan view of the same.

I claim:

The ornamental design for a drip coffee-pot, as shown.

RICHARD F. KRAUSE.
